UNITED STATES PATENT OFFICE.

THOMAS H. ROSENBERGER, OF LOS ANGELES, CALIFORNIA, ASSIGNOR TO ANDREW F. ROSENBERGER, OF CHICAGO, ILLINOIS.

OVERLAPPING CARD-INDEX.

1,158,857.

Specification of Letters Patent.

Patented Nov. 2, 1915.

Application filed February 6, 1914. Serial No. 816,900.

To all whom it may concern:

Be it known that I, THOMAS H. ROSENBERGER, a citizen of the United States, and a resident of the city of Los Angeles, county 5 of Los Angeles, and State of California, have invented certain new and useful Improvements in Overlapping Card-Indexes, of which the following is a specification.

This invention relates to improvements in 10 indices and refers more particularly to a type of card index in which the cards are supported upon a series of leaves or frames, the cards lying in overlapping relation to expose the title of each particular card.

15 Among the salient objects of the invention are to provide improved means for supporting a plurality of overlapping cards mounted in a supporting frame in a novel manner; to provide improved means for adjustably 20 mounting a plurality of overlapping cards in such a way that any of the cards may be removed from the frame without disturbing the mechanical security of the other cards; to provide a construction in which the cards 25 are supported in the frame by being simply hinged on an individual support which preferably may be a simple shaped wire; to provide a construction in which a maximum amount of identifying data may be placed 30 in a minimum amount of space and yet be so arranged as to be instantly accessible; to provide a construction in which the cards are securely held in place and which nevertheless may be readily removed from or 35 inserted in the frame; and in general to provide an improved construction of the character referred to.

In the drawings—Figure 1 represents the upper part of one of the leaves of my 40 proved card index, with one of the side flanges broken away to show the spacing of the supporting wires; Fig. 2 is a section along line 2—2 of Fig. 1; Fig. 3 is a vertical section taken along line 3—3 of Fig. 2 and 45 showing a single supporting wire and part of the card which it supports; Fig. 4 is a similar section taken along line 4—4 of Fig. 2; and Fig. 5 shows one of the card blanks before it is hung over one of the supporting 50 wires.

Referring to the drawings—1 represents as a whole the supporting leaf or frame for the cards, which preferably consists of a flat sheet of thin metal. It comprises a back 55 portion and two longitudinal edges which

are folded over to form the side retaining flanges 2 and 3, spaced slightly from the main sheet of the leaf to form a pair of opposed grooves or channels, within which the supporting wires for the cards are arranged to slide.

In actual practice there may be from one to a hundred or any number, of leaves, each of which may carry from fifty to one hundred individual cards, and in some cases, to 65 allow for increased capacity and to save space, pairs of leaves are joined together back to back to form double leaves with a series of cards arranged upon each side. The various leaves may be mounted vertically upon pivots on a revolving stand, or 70 in any other suitable manner.

The card blank 4, as shown in Fig. 5, is printed upon each of its sides with the particular form necessary for the data to be 75 written upon it. The form shown is one in which it is desired to make a record of orders, shipments and remittances to each individual customer of an ordinary wholesale establishment. The supporting wire 5 is 80 constructed from a length of fairly stiff wire, yet which may be formed easily and which has considerable longitudinal resiliency. The ends of the wire are curved around in U-shape, as shown in Figs. 1 at 6, 85 85 in order to provide for the proper spacing between the individual cards in the index. It is to be noted that the extreme width across the arms of the U will be equal to the width of the space provided for the name 90 written upon the lower edge of the card, as it will have the effect of making the card overlap just the same amount as the wires are spaced apart. Each wire is formed up at two points between its ends to provide a 95 pair of retaining arms or lugs 7, 7 which are each spaced apart from the ends the same distance, making the wire symmetrical. The distance between the arms 7, 7 is such that they will enter freely the two holes 8, 8, 100 punched in the card 4.

Referring to Figs. 2, 3 and 4, it will be seen that the arms 7 are curved slightly and point downward, being of such a length that they contact with the main sheet of the leaf 105 1, and are held in spring engagement therewith by the resiliency of the supporting wire, the ends of which are curved as shown at 9, so as to bring the straight portion of the wire some distance in front of and away 110

from the leaf. The object of this spacing is to make it easy for the cards to swing or hinge about the supporting wires without any possibility of the fold interfering with or rubbing against the surface of the leaf. Interference with the curved portions 9 is prevented by cutting a V-shaped notch 12 positioned at each side of the center of the card. To make the cards more flexible and 10 to prevent them from standing out at an angle from the leaf, the flexibility of the fold is increased by scoring the surface of the card for a short distance on either side of the fold, as indicated at 10. This scoring is 15 accomplished by a method similar to that used in making leaves for loose-leaf ledgers, or other purposes where the loose leaf is made of comparatively heavy, stiff paper, which, however, must lie flat and hinge 20 freely. The arms 7 of the supporting wire perform a double function. In the first place, they prevent the cards from moving longitudinally of the supporting wire, and the cards are thus always in proper alignment; and, in the second place, they prevent 25 the dislodgment of the cards when they are lifted up to expose the cards below, the under-surface of the arms 7 engaging the edges of the apertures 8 whenever there is 30 any tendency for the card to rise away from its supporting wire.

To insert a new card, the latter is first folded double and almost flat, and it is then hung over one of the supporting wires, 35 which it is understood has not yet been placed in the leaf. Then, with the card hanging from the wire, the latter is bowed sufficiently to bring the two ends of the wire together close enough to enable it to enter 40 between the flanges of the leaf. After both ends of the wire have entered behind the flanges, the wire is released and springs back into its normal position, as shown, and is retained in that position by the difference be- 45 tween the length of the supporting wire and the distance between the two opposed edges of the retaining flanges on the leaf. Individual cards may be removed by lifting up the lower edges of the cards above the par- 50 ticular one to be removed until there is space enough between them to permit the supporting wire and card to be grasped and pulled bodily out of the leaf. After a card has been removed, the cards above slide down- 55 wardly under the influence of gravity, if a vertical leaf is used, until the adjacent wires are again all in contact with each other. Insertion of a new card in proper alphabetical arrangement between a number of other cards may also readily be accomplished by 60 sliding the cards apart until the space to permit the insertion of a new card is made.

In the embodiment illustrated in the drawings, I have shown a card which has been folded exactly double, so that the two

lower edges thereof are even with each other. This allows both sides of the card to be used for entering information or data thereon. If, however, all of this space is not required, the under flap of the card may be severed 70 longitudinally at a point a sufficient distance from the hinge to prevent the holes 8 from being weakened or tearing out. This is indicated by the dotted line 11 in Fig. 5. If the flexibility of the index to make it adjust- 75 able for changes in the names is a more or less secondary consideration, in order to save expense, two names may be written on each double card by overlapping the latter slightly when folding, the central holes 8 80 being offset slightly from the center of the card for that purpose. This provides in effect two cards hung upon a single supporting wire, the name being written upon the lower edge of each card. When this is done, 85 however, it is necessary either to change the forming of the ends 6 of the supporting wires to furnish a double spacing between the adjacent cards, or it is necessary to cut in half the width of the name space at the 90 bottom of each card.

I do not limit myself to the details of construction shown, except as specified in the appended claims.

I claim as my invention—

1. In a device of the character described, the combination with a leaf-like frame having oppositely disposed retaining members at its sides, of a plurality of supporting wires detachably seated in said retaining members and having offsets intermediate their ends and cards mounted on said wires in overlapping relation and apertured to receive said offsets.

2. In a device of the character described, the combination with a leaf-like frame having oppositely disposed channels at either side thereof, of a card adapted to receive identifying data thereon folded along a line intermediate its ends and apertured at the fold, a supporting wire having an offset adapted to enter the aperture of the card and provided at its ends with retaining portions fitting into said channels.

3. In a card index, the combination with a supporting leaf having opposed retaining flanges at two opposite sides thereof, and a plurality of superimposed index units mounted on said leaf, each consisting of an apertured card folded along a line intermediate its ends, and a supporting wire therefor having enlarged end-portions shaped to fit behind the flanges to space adjacent wires from each other and provided intermediate its ends with a projection adapted to enter the aperture in said card and hold the latter in place on the wire.

4. In a device of the character described, the combination of a card folded along a line intermediate its ends and apertured at

the fold, and a supporting wire longitudinally resilient and having its ends suitably shaped to prevent improper twisting of the wire when placed in a suitable, supporting frame, and having an integrally formed projecting arm at a point intermediate its ends and adapted to enter the aperture in said card to hold the latter in position, the card being rotatably hung upon said wire,

the fold thereof forming a hinge, said supporting wire having a straight portion suitably spaced apart from the front of the frame to allow the card to hinge freely. 10
